CLAIM

The ornamental design for a mini pocket hole jig, as shown and described.

DESCRIPTION

FIG. 1 is a top elevational view of a mini pocket hole jig;
FIG. 2 is a bottom elevational view of a mini pocket hole jig;
FIG. 3 is a side elevational view of a mini pocket hole jig;
FIG. 4 is another side elevational view of a mini pocket hole jig;
FIG. 5 is a rear elevational view of a mini pocket hole jig;
FIG. 6 is a front elevational view of a mini pocket hole jig;

FIG. 7 is a top rear perspective view of a mini pocket hole jig;

FIG. 8 is another top rear perspective view of a mini pocket hole jig;

FIG. 9 is a bottom rear perspective view of a mini pocket hole jig;

FIG. 10 is another bottom rear perspective view of a mini pocket hole jig;

FIG. 11 is a top front perspective view of a mini pocket hole jig;

FIG. 12 is another top front perspective view of a mini pocket hole jig;

FIG. 13 is a bottom front perspective view of a mini pocket hole jig;

FIG. 14 is another bottom front perspective view of a mini pocket hole jig;

FIG. 15 is a top rear perspective view of a mini pocket hole jig, shown in connection with an attached tail section, as shown in dashed lines for intended use purposes;

FIG. 16 is another top rear perspective view of a mini pocket hole jig, shown in connection with an attached tail section, as shown in dashed lines for intended use purposes;

FIG. 17 is a bottom rear perspective view of a mini pocket hole jig, shown in connection with an attached tail section, as shown in dashed lines for intended use purposes;

FIG. 18 is a top front perspective view of a mini pocket hole jig, shown in connection with an attached tail section, as shown in dashed lines for intended use purposes;

FIG. 19 is a top rear perspective view of a mini pocket hole jig, shown in partial connection with an attached tail section, as shown in dashed lines for intended use purposes;

FIG. 20 is a top rear perspective view of a mini pocket hole jig, shown in connection with an attached tail section, a spacer, and a second mini pocket hole jig and attached tail section, as shown in dashed lines for intended use purposes;

FIG. 21 is another top rear perspective view of a mini pocket hole jig, shown in connection with an attached tail section, a spacer, and a second mini pocket hole jig and attached tail section, as shown in dashed lines for intended use purposes;

FIG. 22 is bottom rear perspective view of a mini pocket hole jig, shown in connection with an attached tail section, a spacer, and a second mini pocket hole jig and attached tail section, as shown in dashed lines for intended use purposes;

FIG. 23 is a top front perspective view of a mini pocket hole jig, shown in connection with an attached tail section, a spacer, and a second mini pocket hole jig and attached tail section, as shown in dashed lines for intended use purposes; and,

FIG. 24 is a top rear exploded perspective view of a mini pocket hole jig, shown in connection with an attached tail section, a spacer, and a second mini pocket hole jig and attached tail section, as shown in dashed lines for intended use purposes.

The dashed lines shown represent the environment and represent unclaimed subject matter and form no part of the claimed design.
